RAILWAY HOPPER CAR

Charles F. Frede and Harry E. Thiele, St. Louis, Mo., assignors to General Steel Castings Corporation, Granite City, Ill., a corporation of Delaware

Application August 13, 1934, Serial No. 739,532

2 Claims. (Cl. 105—249)

This invention relates to railway rolling stock and consists in novel underframe structure for hopper cars.

It has been suggested to form the individual hoppers in hopper cars as unitary castings which are secured to the remainder of the underframe, or to form several hoppers and the center sill with the entire underframe as an integral casting. The adjacent hopper end walls frequently merge to form transverse bracing members for the underframe. However, in such structures the thin broad walls of the hoppers present substantial casting difficulties, particularly due to shrinkage stresses set up during cooling of the metal which tend to strain or rupture the casting.

One object of the present invention is to provide hopper structure in which the hopper walls are corrugated to prevent cracks or other damage in the structure due to shrinkage stresses, the corrugations extending towards the hopper openings so as not to impede dumping.

Another object is to form a plurality of hoppers in an integral casting with the end walls of adjacent hoppers merging to form a transverse bracing member and these walls being provided with longitudinal corrugations extending over the crest of the member for strengthening the same and also for preventing damage due to shrinkage strains.

These objects and others are attained substantially by the structure illustrated in the accompanying drawings, in which—

Figure 1 is a top view of a hopper car underframe embodying the invention.

Figure 2 is a side view and vertical longitudinal section of the same taken on the line 2—2 of Figure 1.

Figure 3 is a vertical transverse section taken on the line 3—3 of Figure 1.

Figures 4 and 5 are partial vertical transverse sections taken on the corresponding section lines of Figure 1.

The hopper car underframe illustrated in the drawings is formed in entirety as an integral casting including the center sill 1, draft sills 2, bolsters 3, side sills 4, and the lower portions of four hoppers generally indicated at 5. The side sills 4 form the upper edges of the outer side walls 6 of the hoppers and the inner walls 7 thereof merge with and are, in part, formed by the side walls of the center sill as shown in Figures 3 and 4. The outer end walls 8 of the hoppers terminate adjacent the upper edge of the center sill and are perforated, as at 9, for attachment to separately

formed slope sheets for continuing the hopper floors upwardly. The inner end walls 10 are provided with hopper openings 11 and brackets 11a for mounting the hopper doors and for operating mechanism (not shown). These walls 10 merge at the center in the substantially inverted V-shaped transverse bracing member designated 12 extending continuously across the underframe and reinforced at the middle by the center sill and at the ends by the side sills. 5

At the intersections of the center sill and bolsters are the gussets 13 and 14, the former being arranged for attachment to underframe diagonal braces (not shown) and the latter having pads 14a for mounting an air brake cylinder 15 (also not shown). The bolsters include side bearings 15 and center bearings 16. 10

The broad thin outer end walls 8 of the hoppers are provided with the corrugations 17 and 17a which prevent weakening or cracking of these 20 walls due to strains set up during cooling of the metal and also substantially strengthening the same without increasing the thickness of the metal. The corrugations 17 for the hoppers at the right hand portion of the car extend parallel 25 to each other and longitudinally towards the hopper openings 11. The corrugations 17a for the hoppers at the left hand portion of the car are wider at their upper ends than at their lower ends to conform with the general contour of the 30 end walls 8. If desired, the corrugations in all of the hopper end walls may be the same as corrugations 17 or corrugations 17a. The outer side walls 6 of the hoppers are provided with corrugations 18 for accommodating shrinkage strains 35 in these parts.

As shown in Figures 1 and 3, the merging end walls 10 of the hoppers on one side of the underframe are provided with longitudinal corrugations 19 extending over the crest of the inverted 40 V-shaped member 12 and towards the hopper openings for preventing damage to this part of the structure due to shrinkage strains and also strengthening the member. On the opposite side of the underframe these corrugations are omitted. 45 It will be understood, however, that both sides of the underframe will preferably be formed identical, the variations in the opposite sides in the drawings being illustrative.

By means of the illustrated structure, all of 50 the broad thin web portions of the casting may be adequately reinforced and arranged to withstand shrinkage strains arising during cooling of the metal. Obviously the corrugations may be varied as to size and also as to disposition, al- 55

though preferably they will be disposed towards the hopper openings as illustrated so as not to impede dumping.

Various details of the underframe are not essential and these may be modified. If desired, one or more of the hoppers may be formed integrally and joined with the remainder of the structure. These modifications and others as will occur to those skilled in the art may be made 10 in the illustrated structure without departing from the spirit of the invention and the exclusive use of all such modifications as come within the scope of the claims is contemplated.

What is claimed is:

15 1. A hopper car integral cast structure including adjacent hopper end walls merging in a trans-

verse bracing member, there being longitudinal corrugations in said member extending over the crest thereof and downwardly on each side towards the hopper openings.

2. A hopper car integral cast structure including adjacent hoppers with their end walls corrugated to relieve said walls of shrinkage strains, adjacent walls of said hoppers merging in a substantially inverted V-shaped member, all of the corrugations extending towards the hopper 10 openings and the corrugations in said merging walls extending continuously over the crest of said member.
